UNITED STATES PATENT OFFICE.

JOSEPH FRANCOIS PARADIS, OF MONTREAL, QUEBEC, CANADA, ASSIGNOR OF ONE-HALF TO RENE CHIQUETTE, OF MONTREAL, QUEBEC, CANADA.

LACE FASTENER.

Application filed April 6, 1922. Serial No. 550,174.

To all whom it may concern:

Be it known that I, JOSEPH FRANCOIS PARADIS, a citizen of the United States of America, and residing at the city of Montreal, in the Province of Quebec, in the Dominion of Canada, have invented a new and useful Lace Fastener, of which the following is the specification.

The invention relates to a lace fastener as described in the present specification and illustrated in the accompanying drawings that form part of the same.

The invention consists essentially of the novel features of construction pointed out broadly and specifically in the claims for novelty following a description in detail of the preferred form of the invention.

The objects of the invention are primarily to avoid the inconvenience and annoyance caused by the undoing of the tie in boot and shoe laces, to facilitate the fastening of the shoe laces, and generally to provide a simple fastening that is particularly suitable for shoe laces though applicable to any fastening in which laces or cords are used.

In the drawings, Figure 1 is a perspective view of a shoe having the fastener applied thereto.

Figure 2 is a detail showing a plan view of the clamp hook fastener enlarged.

Figure 3 is a detail showing a side elevation of the clamp hook.

Like numerals of reference indicate corresponding parts in the various figures.

Referring to the drawings, the hooks 1 are mounted on the uppers 2^a and 3 respectively of the shoe, each hook having the widely spread eye pieces 4 and 5 by means of which

it is firmly sewed to the leather of the shoe, and the clamping hook 6 depressed at 7 between the eye pieces 4 and 5, so as to bring the hook at that point in the same plane as the upper surfaces of said eye pieces. The bill 8 is outwardly turned from the depression 7 in order to facilitate the insertion of 45 the lace 9 under the depression into the comparatively narrow space between the hook 6 and eye pieces 4 and 5, where the lace is squeezed but not damaged to the extent of being cut or torn.

In the use of the fastener the shoe is laced in the ordinary manner and at the cop one crossed lace being inserted in the hook 1 and the other in the hook 2, where they are held until released, thereby obviating the necessity of tying the laces together as is customarily done in fastening shoe laces.

This may be applied to corsets or other garments having lace fasteners and in making is preferably formed from a length of 60 wire, which is bent into shape terminating in the eye pieces 4 and 5 for securing it to the shoe or garment.

What I claim is:

A lace fastener comprising a hook having 65 widely spread eye bars converging to a central hook, the latter forming a lace fastening loop with said eye bars at the point of convergence of slightly less dimensions than a lace and extending on the same plane as 70 the outer surface of said eye bars and outwardly turned at the point.

Signed at Montreal, Canada, this 23 day of March, 1922.

JOSEPH FRANCOIS PARADIS.
